by William R. Baird

His Atty.

UNITED STATES PATENT OFFICE.

JOHN SLATER, OF BROWN EDGE, STOKE-UPON-TRENT, ENGLAND,
ASSIGNOR TO WILLIAM S. PITCAIRN, OF NEW YORK, N. Y.

DESIGN FOR A JUG OR SIMILAR ARTICLE.

No. 38,054.

Specification for Design.

Patented June 5, 1906.

Application filed April 16, 1906. Serial No. 312,036. Term of patent 3½ years.

To all whom it may concern:

Be it known that I, JOHN SLATER, a subject of the King of Great Britain, residing at Brown Edge, Stoke-upon-Trent, England, have invented a certain new, original, and ornamental Design for Jugs or Similar Articles, of which the following is a specification.

In the accompanying drawing the figure is an elevation showing the design for the jug.

What I claim is—

The ornamental design for a jug or similar article substantially as shown.

JOHN SLATER
